Augustus Quackenbush, Albany, N. Y. - Assignee of Samuel W. Gibbs, Albany, N. Y.

Letters Patent No. 222 - Dated June 26, 1844.

The Schedule referred to in these Letters Patent and making part of the same.

To all whom it may concern:

Be it known that I, Samuel W. Gibbs of the City of Albany and State of New York, have produced a new Ornamental design for Cooking Stoves, called the Model Air tight, and I do hereby declare that the annexed and accompanying drawing is a full and accurate delineation of a Stove arranged after my Design: the side not seen resembling the side shewn in the drawing and the Back plate having no special ornament distinguishing it from other Stoves.

What I claim as my invention and design to secure by Letters Patent is the Ornamental design of a Stove plates for a cooking Stove as represented in the accompanying drawing.
